FRICTION LETOFF FOR LOOMS

Louis P. Randall and Miles W. Snipes,
Lancaster, S. C.

Application April 17, 1952, Serial No. 282,824

15 Claims. (Cl. 139—107)

1

This invention relates to textile looms and, more especially, to an improved constant tension friction let-off therefor.

There are at least two general types of let-off mechanisms in common use today in high speed looms, which let-off mechanisms are commonly termed as positive let-offs and friction let-offs. As is well known, the positive let-offs of the Bartlett or the Roper types, employ positive actuating means acting through a braking mechanism to cause the warp beam to rotate and thus pay off the warp intermittently. However, the intermittent operation of the positive type of let-offs has not been entirely satisfactory because they permit periodic variations in tension of the warp yarns or threads which result in so-called thick and thin places in the woven cloth which results in wavy cloth and the production of "seconds" with consequent loss to the textile mill operator.

The friction type let-off has proven more satisfactory, since the warp is let off uniformly and constantly and, therefore, it is the primary object of this invention to provide a friction let-off mechanism which may be more simply constructed, installed and maintained than friction let-offs heretofore employed and which is more efficient in maintaining uniform tension in the warp yarns or threads than friction let-offs which are currently in use.

It is an object of this invention to provide an improved friction let-off for looms wherein a warp beam is provided with a gear and a speed multiplying gear is connected to said warp beam gear and wherein a rotor friction element is driven by said speed multiplying gear, the improvement including a stator friction element restrained from rotation and means controlled by variations in the diameter of the warp wound on the warp beam for varying the pressure of the stator friction element against the rotor friction element, said means comprising a first cam member adapted to move with a follower arm arranged to bear against the yarn on the warp beam and said first cam member bearing against a second cam member fixed on a pressure applying mechanism bearing against the surface of the stator friction element remote from that surface which engages the rotor friction element and whereby relative movement between the first and second cam members causes the pressure applying mechanism to move relative to the rotor friction element to, in turn, control the pressure of the stator friction element against the rotor friction element and, of course, controlling the

2

tension in the warp yarns as they are paid off from the warp beam.

It is another object of this invention to provide a friction let-off mechanism of the character last described with manually operable means for quickly releasing the pressure applying mechanism from engagement with the stator friction element to thereby permit an operator to rotate the warp beam without being encumbered by the friction let-off mechanism, as may be desirable in the event of a "smash," i. e., the breaking of a plurality of the warp yarns at the fell of the cloth or for any one of many other reasons well known to those familiar with the art.

It is still another object of this invention to provide means for controlling the amount of tension effected by the friction let-off mechanism in the warp yarns relative to the friction effected between the rotor and stator friction elements by the first and second cam means heretofore described. In other words, a means is provided for varying the amount of pressure exerted by the pressure applying mechanism on the stator friction element although the first and second cam members are not moved relative to each other.

Some of the objects of the invention having been stated, other objects will appear as the description proceeds when taken in connection with the accompanying drawings, in which—

Figure 1 is a fragmentary side elevation of the rear portion of the left-hand side of a loom showing the improved friction let-off in association therewith and showing the movable cam member in alternate positions;

Figure 2 is an elevation, with parts broken away, looking at the left-hand side of Figure 1 and showing only the portion of the loom adjacent the improved friction let-off mechanism;

Figure 3 is a fragmentary sectional plan view looking down substantially along the line 3—3 in Figure 1;

Figure 4 is an enlarged fragmentary vertical sectional view, mostly in elevation, taken substantially along the line 4—4 in Figure 3;

Figure 5 is a view similar to Figure 4 but showing the parts in a different position;

Figure 6 is a vertical sectional view, mostly in elevation, taken substantially along the line 6—6 in Figure 1 with parts broken away;

Figure 7 is an enlarged vertical sectional view taken substantially along the line 7—7 in Figure 1;

Figure 8 is a fragmentary top plan view of the structure shown in Figure 4;

Figure 9 is a vertical sectional view, on a reduced scale, taken substantially along the line 9—9 in Figure 7 and showing the rotor friction element in elevation;

Figure 10 (Sheet 2) is a fragmentary isometric view of the pressure applying disk and lever which are instrumental in effecting movement to the stator friction element and looking substantially along line 10—10 in Figure 7.

Referring more specifically to the drawings, the numeral 10 indicates the side frame member of a loom to which one end of a transverse frame member or girt 11 is suitably secured, there being a side frame member similar to the frame member 10 positioned at the other side of the loom, not shown, for supporting the other end of the girt 11. Each of the side frame members 10 has a bracket 12 secured thereto which brackets support opposite ends of a shaft 13 of a warp beam 14 for rotation therein. The opposite ends of the warp beam 14 each has a disk or head 15 thereon and warp yarns Y are wound about the warp beam 14 between the disks 15.

The warp yarns Y extend upwardly in Figure 1 from the warp beam 14 and pass over a guide roll or whip roll 16 supported for rotation in brackets 17 which extend forwardly and are secured to a transverse whip roll shaft 20 oscillatably mounted in suitable brackets 21 secured to the side frame members 10 of the loom. Although only a single one of each of the brackets 17 and 21 is shown, it is evident that similar brackets are disposed at the opposite side of the loom.

The yarns Y then pass forwardly from the whip roll 16 through the usual weaving instrumentalities, not shown, and then to a suitable take-up mechanism shown schematically at 23 in Figure 1. This take-up mechanism may be the usual sand roll of the loom. The disk or beam head 15 has a relatively large gear 24 fixed thereon which meshes with a speed multiplying gear or pinion 25 fixed on the inner end of a let-off shaft 26 which is a part of the improved friction let-off mechanism broadly designated at 27 and which will be later described in detail.

The shaft 26 is rotatably mounted in a let-off shaft bracket 30 suitably secured to the inner surface of the side frame member 10, and also being suitably secured to the transverse frame member or girt 11 (Figure 2). A conventional beam lever or follower arm 33 bears against the warp on the warp beam 14. This beam lever 33 extends downwardly and the lower end thereof is fixed on one end of a beam lever shaft 34 oscillatably mounted in a beam lever bracket 35 suitably secured to the side frame member 10.

A suitable spring means is provided for normally urging the free end of the beam lever 33 against the warp wound about the warp beam 14 and, to this end, a beam lever spring in the form of a torsion spring 37 surrounds the shaft 34 and one end of the spring 37 is secured to the bracket 35, the other end thereof being secured to the shaft 34. Collars 38, fixed on shaft 34, prevent endwise movement of shaft 34 relative to bracket 35. The parts heretofore described are conventional parts of the usual types of looms having a let-off mechanism associated therewith and it is with these parts that the improved friction let-off mechanism 27 is adapted to be associated. The drawings show only a portion of a weaving loom since a description of the remain-

ing parts of the loom is not necessary for a complete understanding of the present invention.

The improved friction let-off 27 comprises a stator friction element 40 and a rotor friction element 41. The stator and rotor friction elements 40 and 41 are shown in the form of disks, the stator friction disk 40 being provided with peripheral flange 42 which projects inwardly toward the frame member 10 and loosely encircles the rotor friction disk 41. The rotor friction disk 41 is provided with a plurality of friction blocks 43 which project outwardly therefrom and frictionally engage the proximate surface of the stator friction disk 40.

15 The friction blocks 43 are preferably formed from cork or other friction material. It is to be understood that a disk of friction material may be secured to either the stator or rotor friction element 40 or 41 in lieu of the friction blocks 43, if desired. The rotor friction element 41 is suitably secured on the let-off shaft 26, as by a key 44 and a set screw 45, said set screw threadably penetrating the hub of the rotor friction element 41. Thus, the hub of the rotor friction element 41 slidably and rotatably engages the outer surface of the bracket 30, which bracket loosely penetrates a suitable opening 46 in the side frame member 10 of the loom.

20 The shaft 26 penetrates the hub of the stator friction element 40 for rotation relative thereto and the outer end of the shaft 26 also loosely penetrates a pressure applying disk 47 of a pressure applying mechanism designated broadly at 50 (Figures 1, 2, 3, 6, 7, 8 and 10). The inner surface of the pressure applying disk 47 bears against the outer surface of the hub of the stator friction element or disk 40 as is clearly shown in Figures 3, 6 and 7. As best shown in Figures 1 and 10, the pressure applying mechanism 50 25 also comprises a pressure applying lever arm 51 provided with an enlarged annular portion 52 intermediate the ends thereof which loosely surrounds the pressure applying disk 47 and is provided with a pair of diametrically opposed grooves or slots 53 therein.

30 The pressure applying disk 47 has a pair of diametrically opposed projections 54 integral therewith which are preferably circular in cross-section and slidably penetrate the grooves or slots 53 in the annular portion 52 of the lever arm 51. The lever arm 51 and the pressure applying disk 47 may be integral, if desired. However, the lever arm 51 pivots about a vertical axis as it moves inwardly and outwardly relative to the shaft 26 and the present structure facilitates uniform engagement of the pressure applying disk 47 against the hub of the stator friction element 40.

35 The frame of the improved let-off mechanism 27 comprises a standard 60 (Figures 1, 2, 3, 4, 5, 6 and 8) on which the rear end of the pressure applying lever arm 51 may be pivotally mounted for pivotal movement about a vertical axis. However, a novel means is provided to permit pivotal movement of the rear end of the lever arm 51 which means facilitates adjustment of the corresponding end of the lever arm inwardly and outwardly relative to the rotor friction element 41 and which is quickly releasable to facilitate manual rotation of the warp beam 14 without being encumbered by the improved friction let-off 27.

40 To this end, it will be observed in Figures 4 and 5 that the upper end of the standard 60 is spaced outwardly from the rear end of the pres-

sure applying lever arm 51 and has a cavity 64 in the inner face thereof which is preferably polygonal in cross-section for slidable reception of a plunger 62. The plunger 62 is engaged by an adjustment screw 63 which threadably penetrates the upper end of the standard 60 and has a hand wheel 64 fixed on the outer end thereof for manipulation by an operator. The screw 63 is provided to vary the position of the plunger 62 relative to the standard 60 for purposes to be later described. A suitable lock nut 65 is threadably mounted on the screw 63 for locking the same in any desired adjusted position.

The bifurcated inner end of the plunger 62 has a follower wheel or roller 66 rotatably mounted therein which normally engages an eccentric cam 66 fixed on a shaft 67 which is held against the outer surface of the corresponding end of the lever arm 51, in parallel relation to the longitudinal axis thereof, by suitable bearing blocks 70. The bearing blocks 70 are suitably secured to the outer surface of the lever arm 51 as by welding (Figure 8).

It will be observed in Figures 2 and 8 that the shaft 67 extends rearwardly and is bent at right angles to form a handle portion 71 which is adapted to be manipulated by an operator for varying the position of the eccentric cam 66 as shown in Figures 4 and 5. The lever arm 51 is provided with a cavity 12 to accommodate the cam 66 when it faces inwardly as shown in Figure 5. It will be noted that the cam 66 is provided with a notch 73 in the periphery thereof and at the high point thereof, which notch 73 is adapted to be engaged by the follower wheel 66 when the cam 66 is in the position shown in Figure 4, this being the normal operative position of the cam 66 during operation of the improved friction let-off 21.

It is thus seen that the pressure applying lever arm 51 may pivot about a vertical axis relative to the follower wheel 66. The notch 73 in the eccentric cam 66 is maintained in engagement with the roller or follower wheel 66 due to the pressure of the rotor friction element 41 against the stator friction element 40 which pressure is transmitted to the cam 66 through the pressure applying mechanism 50.

The front portion of the pressure applying lever arm 51 normally bears against the lower surface of the horizontal leg of an inverted substantially L-shaped gauge member or guide 74 (Figures 1, 2, 3 and 6). The gauge member 74 is provided to assist an operator in properly positioning the lever 51 when it is installed as shown in the drawings. The front end of the lever arm 51, that is, the end remote from the eccentric cam 66, has a longitudinally extending cam member 75 (Figures 1, 3, 6 and 7) suitably secured thereto or which may be an integral part thereof. The front portion of the cam 75 is substantially thicker than the rear portion thereof, as is clearly shown in Figures 3 and 7, so the outer surface of the rear end of the cam 75 adjacent the disks 40, 41 is positioned closer to the disks than the front end of the cam 75 in planes parallel to the axis of the disks 40, 41. The outer surface of the cam 75 is engaged by a follower, shown in the form of a wheel 76 (Figures 3, 6 and 7) rotatably mounted in a bracket 77 suitably secured to the inner surface of an auxiliary cam follower arm 83 (Figures 1, 2, 3, 6 and 7).

The cam follower arm 83 extends downwardly and is fixed on the outer end of the beam lever shaft 34 heretofore described. The frame to

which the lower ends of the standard 60 and the gauge member 74 are secured may be of cast construction, if desired. However, in this instance, the frame comprises a pair of lateral frame members 82 and 83, the outer ends of which are suitably secured to the respective rear and front ends of a bridging frame member 84.

The frame member 83 extends inwardly and is then bent upwardly and is suitably secured to the side frame member 10. The frame member 82 also extends inwardly and is then bent upwardly and suitably secured to the frame member 10. However, this frame member is also bent outwardly at its upper end and then downwardly, as at 90 (Figure 6), to serve as a support for an upper restraining arm 91 suitably secured thereto, as by a screw 92. The outer end of an angularly disposed bracing member 93 is suitably secured to the lower surface of the member 82, this bracing member 93 extending downwardly and inwardly and being suitably secured at its lower end to the side frame member 10.

A lower restraining member 94 is suitably secured intermediate the ends of the lower horizontal portion of the frame member 82 and the two restraining members 91 and 94 extend forwardly and are pivotally connected, as at 95 (Figure 7), to respective blocks 96 suitably secured to the outer surface of the stator friction element or disk 40.

The pivotal connections 95 (Figures 1, 2, 6 and 7) between the restraining members 91 and 94 and the blocks 96 are shown in the form of shoulder screws to permit movement of the stator friction disk 40 longitudinally of the shaft 26 and relative to the restraining members 91 and 94.

It is thus seen that the restraining members 91 and 94 restrain the stator friction element or disk 40 from rotation. Although the enlarged annular portion 52 (Figures 1 and 10) of the lever arm 51 loosely surrounds the pressure applying disk 47, the lever 51 is held in the position shown due to the pressure between the stator friction element 40 and the cam 75 and the cam 66 (Figures 1, 4, 5, 7 and 8).

In operation, the pressure of the stator friction element 40 against the friction blocks 43 on the rotor friction element 41 gradually decreases as the diameter of the warp wound about the warp beam 14 decreases because of the outer surface of the front ends of the cam member 75 being spaced further from the disks 40, 41 than the outer surface of the front end thereof and, of course, when the warp on the warp beam 14 is of relatively large diameter. As the warp yarns Y are paid off of the warp beam 14, the diameter of the warp decreases whereupon the torsion spring 31 (Figures 3 and 6) causes the beam lever 33 to move in a counter-clockwise direction in Figure 1, moving the auxiliary follower arm 83 accordingly.

Since the outer surface of the cam 75 nearest the shaft 26 is spaced closer to the rotor friction element 41 than the outer surface of the remote or free end of the cam 75, this gradually relaxes the pressure of the stator friction element 40 against the rotor friction element 41 thereby insuring that the yarns Y are maintained under a constant uniform tension regardless of the diameter of the warp wound about the warp beam 14.

It occasionally becomes necessary for an operator to rotate the warp beam 14 in either direction, such as when replacing an empty warp beam with a filled warp beam or for various other reasons and, in order that the operator is not en-

cumbered by the friction let-off mechanism, it is merely necessary for the operator to grasp the handle portion 71 and to rotate the shaft 67 to move the cam 66 from the position shown in Figure 4 to the position shown in Figure 5. This will simultaneously permit the pressure applying mechanism 50 to move outwardly relative to the friction disks 40, 41 and thereby permit free rotation of the rotor friction element 41 and the let-off shaft 26. After the operator has rotated the warp beam 14 as desired, the lever arm 51 is held in the proper position relative to the pressure applying disk 41 as the cam 66 is returned to the position shown in Figure 4 to again cause the stator friction element 40 to bear against the friction blocks 43 on the rotor friction element 41.

As is well known, the tension required in the yarns Y varies with different types of yarns, the amount of twist in the yarns and the type of cloth into which the yarns are to be woven. Accordingly, the tension in the yarns Y may be varied relative to a particular diameter of the warp on the warp beam without changing the position of the follower 76 on the cam follower arm 80 relative to the cam 75 by adjusting the adjustment screw 63 in the manner heretofore described (Figures 1, 4 and 5). It is evident that this varies the amount of pressure exerted on the disk 40 by the pressure applying mechanism 50 (Figure 10) relative to the follower 76 (Figures 3, 6 and 7) on the arm 80 being in engagement with a given point on the cam 75. The peripheral flange 42 (Figure 7) on the stator friction element or disk 40 serves to shield the friction blocks 43 from lint and other foreign matter.

It is thus seen that we have provided an improved friction left-off mechanism of simple construction with resultant economy in producing and maintaining the same and wherein means are provided for compensating for the decrease in diameter of the warp on the warp beam by accurately varying the pressure between the friction surfaces of the let-off mechanism. Moreover, a means is provided to adjust the pressure between the friction surfaces of the let-off mechanism so the tension in the warp yarns may be varied relative to a given diameter of the warp on the warp beam. It is also evident that the pressure between the friction surfaces of the let-off mechanism may be quickly released to facilitate manual rotation of the warp beam or to relieve the tension in the warp yarns during periods in which the loom may not be in operation thereby assisting in preventing the occurrence of "set-marks" in the woven cloth.

In the drawings and specification, there has been set forth a preferred embodiment of the invention and, although specific terms are employed, they are used in a generic and descriptive sense only, and not for purposes of limitation, the scope of the invention being defined in the claims.

We claim:

1. In a loom having a rotatable warp beam provided with warp threads wound thereon, an improved friction let-off comprising a first friction disk, a driving connection between the warp beam and said first friction disk for imparting rotation to the first friction disk, a second friction disk restrained from rotation and frictionally engaging said first friction disk and cam controlled means responsive to variations in the diameter of the warp on the warp beam for maintaining said friction disks in pressure engage-

ment and for, accordingly, varying the pressure of the friction disks relative to each other.

2. In a loom having a rotatable warp beam provided with warp wound thereon, a friction let-off mechanism having its input end connected to said warp beam, a stationary element and a rotary element connected to the output end of said mechanism and having juxtaposed surfaces in sliding engagement, a manually movable cam means normally applying pressure to said elements, adjustable means normally engaging said cam means and causing said cam means to apply pressure to said elements, means controlled by the diameter of the warp on the warp beam and co-acting with said cam means to reduce the pressure applied to said elements as said diameter reduces, and said cam means being movable out of engagement with the adjustable means to quickly release the pressure on the friction elements relative to each other and to thereby facilitate free rotational movement of the warp beam.

3. An improved friction let-off for a loom having a rotatable warp beam provided with warp wound thereon, a gear on said warp beam and a gear connected to said warp beam gear, said friction let-off mechanism comprising a first friction disk rotatable by said gear connected to the warp beam gear, a second friction disk restrained from rotation and frictionally engaging said first friction disk, a pressure applying mechanism movable axially against at least one of said friction disks for maintaining the said friction disks in pressure engagement, and cam actuated means controlled by the diameter of the warp on the warp beam for moving said pressure applying mechanism axially of the friction mechanism to vary the pressure exerted by the pressure applying disk on the corresponding friction element and to thereby maintain the warp under constant and uniform tension as the diameter of the warp on the warp beam decreases.

4. In a loom having a rotatable warp beam provided with warp wound thereon, the combination of a first rotatable friction element, mechanical connections between the warp beam and the first friction element for imparting rotation from the warp beam to the first friction element, a second friction element restrained from rotation and frictionally engaging said rotatable friction element, an axially movable pressure applying mechanism for maintaining said friction elements in pressure engagement, cam means carried by the pressure applying mechanism, and movable means movable in response to variations in the diameter of the warp on the warp beam and engaging said cam means on the pressure applying mechanism to cause axial movement of the pressure applying mechanism to thereby vary the pressure exerted by the pressure applying mechanism on the friction elements according to the diameter of the warp on the warp beam and to maintain the warp under constant and uniform tension as the diameter of the warp beam decreases.

5. In a loom having a rotatable warp beam provided with warp wound thereon, the combination of a rotatable friction element, means operatively connecting said warp beam to said friction element for causing said friction element to rotate in proportion to the speed of said warp beam, a friction element movable axially into pressure engagement with said rotatable friction element, a pressure applying mechanism for pressing said axially movable friction element into engagement with the ro-

tatable friction element and including a lever, a cam fixed on one end of said lever, follower means engaging said cam to press the pressure applying mechanism into engagement with the axially movable element, means controlled by the diameter of the warp on the warp beam for moving said follower means relative to the cam, and said cam being of such configuration as to cause axial movement of the pressure applying mechanism and the axially movable friction element in a direction to decrease the pressure effected by the pressure applying mechanism on the axially movable friction element as the diameter of the warp on the warp beam decreases.

6. In a loom having a rotatable warp beam provided with warp wound thereon, an improved friction let-off comprising a first friction element, a driving connection between the warp beam and said first friction element, a second friction element restrained from rotation and frictionally engaging said first friction element, cam controlled means responsive to variations in the diameter of the warp on the warp beam for maintaining said friction elements in pressure engagement and for, accordingly, varying the pressure of the friction elements relative to each other, a manually movable cam means normally assisting in maintaining said friction elements in pressure engagement, and means operable automatically upon changing the position of said manually movable cam means relative to the friction elements to release the pressure of the friction elements relative to each other to thereby permit rotation of the warp beam without encumbrance by pressure engagement of the friction elements.

7. In a loom having a rotatable warp beam provided with warp wound thereon, the combination of a first rotatable friction element, mechanical connections between the warp beam and the first friction element for imparting rotation from the warp beam to the first friction element, a second friction element restrained from rotation and frictionally engaging said rotatable friction element, an axially movable pressure applying mechanism for maintaining said friction elements in pressure engagement, cam means carried by the pressure applying mechanism, movable means movable in response to variations in the diameter of the warp on the warp beam and engaging said cam means on the pressure applying mechanism to cause axial movement of the pressure applying mechanism to thereby vary the pressure exerted by the pressure applying mechanism on the friction elements according to the diameter of the warp on the warp beam and to maintain the warp under constant and uniform tension as the diameter of the warp beam decreases, a locking cam normally maintaining the pressure applying mechanism in pressure applying position, and manually operable means for moving the locking cam to quickly release the pressure applying mechanism from pressure applying position to thereby permit the warp beam to be moved without being encumbered by pressure engagement of the friction elements.

8. In a loom having a rotatable warp beam provided with warp wound thereon, the combination of a first rotatable friction element, mechanical connections between the warp beam and the first friction element for imparting rotation from the warp beam to the first friction element, a second friction element restrained from rotation and

frictionally engaging said rotatable friction element, an axially movable pressure applying mechanism for maintaining said friction elements in pressure engagement, cam means carried by the pressure applying mechanism, movable means movable in response to variations in the diameter of the warp on the warp beam and engaging said cam means on the pressure applying mechanism to cause axial movement of the pressure applying mechanism to thereby vary the pressure exerted by the pressure applying mechanism on the friction elements according to the diameter of the warp on the warp beam and to maintain the warp under constant and uniform tension as the diameter of the warp beam decreases, and means to vary the pressure exerted by the pressure applying mechanism in maintaining said friction elements in pressure engagement relative to the variations in pressure effected by the pressure applying mechanism as caused by variations in the diameter of the warp on the warp beam.

9. In a loom having a rotatable warp beam provided with warp wound thereon, an improved friction let-off comprising a first friction element, a driving connection between the warp beam and said first friction element, a second friction element restrained from rotation and frictionally engaging said first friction element, cam controlled means responsive to variations in the diameter of the warp on the warp beam for maintaining said friction elements in pressure engagement and for, accordingly, varying the pressure of the friction elements relative to each other, a second manually rotatable cam means normally assisting in maintaining said friction elements in pressure engagement, means operable automatically upon changing the position of said second cam means relative to the friction elements to release the pressure of the friction elements relative to each other to permit rotation of the warp beam without being encumbered by pressure engagement of the friction elements, and adjustable means engaging said second cam means when the second cam is in pressure applying position relative to the friction elements whereby the pressure effected by the second cam means on the friction elements may be adjusted to vary the pressure of the friction elements relative to each other and relative to a given diameter of the warp on the warp beam.

10. In a loom having a rotatable warp beam provided with warp threads wound thereon, an improved friction let-off comprising a first friction disk, a driving connection between the warp beam and said first friction disk, a second friction disk restrained from rotation and frictionally engaging said first friction disk, cam controlled means responsive to variations in the diameter of the warp on the warp beam for maintaining said friction disks in pressure engagement and for, accordingly, varying the pressure of the friction disks relative to each other, and means to adjust said cam controlled means relative to the friction disks to vary the pressure effected by the cam controlled means relative to a given diameter of the warp on said warp beam.

11. In a loom having a rotatable warp beam provided with warp wound thereon, the combination of a rotatable friction element, means operatively connecting said warp beam to said friction element for causing said friction element to rotate at a speed in proportion to the speed of said warp beam, a friction element movable axially into pressure engagement with said rotatable friction element, a pressure applying mechanism

for pressing said axially movable friction element into engagement with the rotatable friction element and including a lever, a cam on one end of said lever, follower means engaging said cam to press the pressure applying mechanism into engagement with the axially movable element, means controlled by the diameter of the warp on the warp beam for moving said follower means relative to the cam, said cam being of such configuration as to cause axial movement of the pressure applying mechanism and the axially movable friction element in a direction to decrease the pressure effected by the pressure applying mechanism on the axially movable friction element as the diameter of the warp on the warp beam decreases, means to lock said pressure applying mechanism in pressure applying position while said follower means is in engagement with said cam, and manually operable means to move said locking means to inoperative position to release the pressure applying mechanism from pressure applying position to thereby facilitate free rotation of the warp beam and the rotatable friction element.

12. In a structure according to claim 11, means to adjust said locking means relative to the axially movable friction element to vary the pressure effected by the pressure applying mechanism relative to the pressure exerted thereon by the follower means engaging said cam.

13. In a loom having a rotatable warp beam provided with warp wound thereon; the combination of a rotatable friction disk, a driving connection between the warp beam and the rotatable friction disk for imparting rotation from the warp beam to said disk, an axially movable friction disk restrained from rotation and frictionally engaging said rotatable friction disk, a pressure applying mechanism for pressing said axially movable friction disk into engagement with the rotatable friction disk including a lever disposed outwardly of and extending transversely relative to said axially movable friction disk, means pivotally supporting one end of said lever to one side of the axis of the axially movable friction disk and being so arranged as to permit movement of said lever toward and away from the axially movable friction disk, means carried by the medial portion of said lever for pressing against the axially movable friction disk, a cam on the other end of said lever, follower means engaging said cam, means controlled by the diameter of the warp on the warp beam for moving said follower means relative to the cam, and said cam being so configured as to cause axial movement of the pressure applying mechanism and the axially movable friction disk in a direc-

tion to decrease the pressure effected by the pressure applying mechanism on the axially movable friction disk as the diameter of the warp on the warp beam decreases.

5 14. In a structure according to claim 13 wherein said loom has a shaft disposed in spaced substantially parallel relationship to the axis of said friction disks and a beam lever fixed on said shaft and bearing against the warp on said warp beam, said cam being in the form of an elongated member carried by and extending substantially parallel to the portion of said first-named lever remote from the pivoted end thereof, the outer surface of said elongated member being tapered relative to the axially movable friction disk so that one end of the elongated member is disposed further from the axially movable friction disk than the other end thereof, and said follower means including an arm fixed on said shaft and having means thereon engageable with the outer surface of said elongated member carried by the first-named lever.

15 15. In a structure according to claim 13, said means pivotally supporting one end of said lever including a manually rotatable eccentric cam carried by said lever and having a notch in the high point of the periphery thereof, said eccentric cam being mounted on an axis substantially perpendicular to the axis of said disks, a stationary standard spaced outwardly from said eccentric cam relative to the axially movable friction disk, a plunger mounted in said standard for adjustment parallel to axis of said disks, and having means thereon normally engaging the notch in said eccentric cam whereby said lever may pivot at the juncture of the cam with said means carried by the plunger, and whereby manual rotation of said eccentric cam will permit the pivoted end of said lever to move outwardly relative to the first rotatable friction disk to release the axially movable friction disk from pressure engagement with the rotatable friction disk.

LOUIS P. RANDALL.
MILES W. SNIPES.
